UNITED STATES PATENT OFFICE.

CHARLES F. BURKHART, OF BUFFALO, NEW YORK.

DESIGN FOR A BADGE OR SIMILAR ARTICLE.

SPECIFICATION forming part of Design No. 34,392, dated April 23, 1901.

Application filed May 6, 1899. Serial No. 715,886 Term of patent 3½ years.

To all whom it may concern:

Be it known that I, CHARLES F. BURKHART, a citizen of the United States, residing at Buffalo, in the county of Erie and State of New York, have invented and produced a new and original Design for a Badge or Similar Article, of which the following is a specification.

My design relates to the configuration or ornamentation of a badge or similar article.

In the accompanying drawings, Figure 1 is a face view of a badge embodying my design. Fig. 2 is a central vertical section through the same.

The design consists of the representation of a buffalo in a prancing or running position, and bearing on his back is the representation

of a pan or spider; above which is represented an eagle with displayed wings.

Referring to the drawings, A is the representation of a buffalo in a prancing or running position, B is the representation of a pan or spider bearing on the back of the buffalo, and C is the representation of an eagle with outspread or displayed wings perched above the pan or spider.

What I claim is—

The design for a badge or similar article substantially as herein shown and described.

CHAS. F. BURKHART.
